UNITED STATES PATENT OFFICE.

FRANK E. HAGEMAN, OF MILWAUKEE, WISCONSIN, ASSIGNOR TO THE MILWAUKEE ELECTRIC RAILWAY & LIGHT COMPANY, OF MILWAUKEE, WISCONSIN, A CORPORATION OF WISCONSIN.

COIN SORTER.

Application filed June 11, 1923. Serial No. 644,680.

The invention relates to coin-sorters.

The object of the invention is to provide a sorter having concentric cylindrical sorting screens to which the coins are fed, the axis of rotation of said screens being inclined to provide for the discharge of the sorted coins, and the construction permitting of a rapid sorting of large quantities of different sized coins.

10 The invention further consists in the several features hereinafter set forth and more particularly defined by claims at the conclusion hereof.

In the drawings: Fig. 1 is a vertical sectional view through a coin-handling machine embodying the invention; Fig. 2 is a front end view of the machine; Fig. 3 is a detail sectional view taken on the line 3—3 of Fig. 1; Fig. 4 is a view of the rear end of the 20 machine.

In the drawings the numeral 5 designates a base member having a front bracket portion 6 and rear brackets 7 formed integrally therewith or secured thereto.

25 A drum-supporting frame is mounted to swing on the bracket portion 6 and to be clamped in an inclined position to the brackets 7. This frame comprises end plates 8 and 9 secured together in spaced relation by rods 10 bolted to them. The end plate 8 is provided with bearing bosses 11 pivoted on a shaft 12 journalled in bearings 13 of the bracket portion 6. The end plate 9 has brackets 14 secured thereto provided with 30 threaded projections 15 that pass through arcuate slots 16 in the brackets 7 and carry clamping nuts 17 whereby the frame may be clamped to the base in any desired inclined position, the front end plate swinging about 35 the shaft 12 to permit this adjustment.

An outer cylindrical member 18 and cylindrical sorting screens 19 and 20 are concentrically mounted on parts 21, 22 and 23, respectively. The parts 23 are disks mounted 45 on a shaft 24 which is journalled in bearings 25 and 26 in the plates 8 and 9. There are spaces 27 provided between the disks 23 and the screen 20. Each part 22 is in the form of a ring serving to space the screens 19 and 50 20 apart, and is recessed to form spaces 28 between it and the screen 19. Each part 21 is in the form of a ring serving to space the screen 19 and the outer member 18 apart and is recessed to form spaces 29 between

it and the member 18. The members 18, 19 55 and 20 and the rings 21 and 22 are secured to the disks 23 by screws 30, the construction forming a rotatable sorting drum structure supported on the frame with its ends covered by the relatively stationary end plates 8 and 9. An annular grooved ring or pulley 31 is mounted at the forward end of the drum and is here shown as fastened thereto by a screw or screws 30.

The drum is turned by an electric motor 32 which drives the shaft 12 provided with a worm 33 meshing with a worm wheel 34 on a shaft 35, said shaft carrying a pulley 36 connected by a belt 37 with the pulley 31. To tension the belt 37 a lever 38 is loosely pivoted intermediate its ends on the shaft 35 and carries at one end a tensioning roller 39 over which the belt passes, and the other end of said arm is engaged by a spring 40 which is mounted on a rod 41 carried by a 65 supporting stud 42, the pressure of the spring 40 on the lever 38 being regulated by the adjustment of the nuts 39 on the threaded end of the rod 41.

Mechanism for feeding the coins into the 70 drum comprises a chute structure 43 bolted to the front plate 8 and a hopper 44 secured to its upper end. This chute 43 has a cylindrical enlargement 45 between its ends in which a feeder 46 rotates, said feeder being 75 mounted on a shaft 47 carrying a pulley 48 connected by a belt 49 with a pulley 50 on the shaft 35 and consequently driven by the motor 32. This feeder 46 is preferably in the form of a triple scoop, each scoop being 80 formed by a radially extending part 51 and an arcuate part 52, the exterior surface of said part 52 having a relatively close association with a part 53 of the front wall of 85 the chute. A deflector 54 below one side of the hopper extends down into the chute and is spaced from the front side thereof to form a relatively narrow passage 55 through which the coins must pass just previous to 90 their being taken up by the feeder and this prevents too fast a feed of coins to the feeder which would be apt to clog it or otherwise interfere with its proper action.

The delivery end 55 of the chute extends 95 into the space between the end plate 8 and the front disk 23.

The chute structure has a part 56 to which a two-part casing 57 for the gears 33 and 34

is bolted, said casing also providing bearings for the shaft 35. The casing 57, gear 34 and shaft 35 are adapted to swing with the drum about the axis of the shaft 12. To provide for additional support for the shaft 35, a yoke 58 is adapted to be bolted to a bracket 59 by means of a bolt 60 passing through a slot 61 elongated to provide for the swinging of the front end of the drum.

10 The screens 19 and 20 are preferably of sheet metal having holes 62 and 63 punched therein to allow coins of certain size to pass therethrough as, for instance, where nickels, pennies and dimes are to be separated, 15 the screen 19 permits pennies and dimes to pass through it, while the screen 20 permits dimes to pass through it whereby the nickels are temporarily retained in cylinder 20 and gradually work down to the lower end 20 thereof; the pennies are temporarily retained in the space between the cylinders 20 and 19 and gradually work down to the lower end of this space and the dimes are temporarily retained in the space between 25 the cylinders 19 and 18 and gradually work down to the lower end of this space.

Discharge chutes 64, 65 and 66 have flanged portions secured to the brackets 14 in any suitable manner, as by bolts 67. The 30 chute 64 communicates with the cylinder 20. The chute 65 communicates with the space between the cylinders 20 and 19 and the chute 66 communicates with the space between the cylinders 19 and 18. These delivery chutes project outwardly beyond the drum and discharge the coins into receptacles that may be placed beneath them.

With the above construction, while the 40 feeder 46 and the separating drum are rotating, coins deposited in the hopper 44 pass down through passage 55 and are scooped or picked up in certain quantities by the feeder 46 and deposited in the lower portion of the chute 43, from which they are 45 charged by gravity into the sorting drum. During the rotation of the drum the sorting of the coins by the screens 19 and 20 takes place simultaneously with the gravity feed of the coins toward the discharge end 50 of the drum, the passages 27, 28 and 29 permitting the coins to pass along to the exit end of the drum. When the coins have reached the lower end of the drum they are separated and are discharged into the delivery 55 chutes 64, 65 and 66, and, as in the example above given, the nickels pass to the chute 64, the pennies to the chute 65 and the dimes to the chute 66. The construction previously described permits of positioning the drum at that inclination most suitable for the rapid and efficient sorting of the coins being handled.

I desire it to be understood that this invention is not to be limited to any particular form or arrangement of parts except in so

far as such limitations are specified in the claims.

What I claim as my invention is:

1. In a coin sorter, the combination of an inclinable supporting frame including stationary spaced end plates, a rotatable sorting drum disposed between and pivotally mounted on said end plates and including concentrically arranged coin sorting screens forming coin-receiving chambers with said stationary end plates, coin-introducing means carried by the upper end plate, and coin discharge means carried by the lower end plate. 70

2. In a coin sorter, the combination of an inclinable supporting frame including stationary spaced end plates, a shaft journaled in said end plates and extending between them, a sorting drum carried by said shaft and including concentrically arranged coin sorting screens extending between said end plates and forming therewith coin-receiving chambers, means for rotating said drum, coin-introducing means carried by the upper end plate, and coin discharge means carried by the lower end plate. 80

3. In a coin sorter, the combination of a sorting drum disposed to rotate on an incline, a stationary chute for delivering coins to the upper end of said drum, a continuously rotatable feeder in said chute supplying coins to the lower end of said chute in predetermined quantities, and means for delivering sorted coins from the rotating drum. 90

4. In a coin sorter, the combination of a sorting drum disposed to rotate on an incline, a hopper, a relatively stationary chute below the hopper for delivering coins to the upper end of said drum, a continuously rotatable feeder in said chute for supplying coins to the lower end of said chute in predetermined quantities while said drum is rotating, and a restricted passage between the hopper and the space in which said feeder operates. 100

5. In a coin sorter, the combination of an inclinable supporting frame including stationary front and rear end plates, a driven shaft, a pivot connection between said shaft and front end plate, a support for said shaft to maintain said front end plate in an elevated position, means for securing the rear end plate in adjusted position below the elevation of said front end plate, a rotatable sorting drum disposed between said end plates including a shaft journaled in said end plates, means mounted on said front end plate for feeding coins to the upper end of said drum, and means for discharging the sorted coins from the lower end of the drum. 110

6. In a coin sorter, the combination of an inclinable supporting frame having a pivoted upper end, adjustable means for securing said frame in an inclined position, a rotatable sorting drum journaled in said frame, a driven shaft adjacent the upper end 120

- of said frame and adapted to swing therewith, said shaft being disposed adjacent and outside of the periphery of said drum, a driving connection between said shaft and the lower end of said drum, and a driving connection for said drum co-axial with the pivoted support of the drum-supporting frame on the base. 80
- 5 9. In a coin sorter, the combination of a rotatable sorting drum disposed on an incline, a hopper, a relatively stationary chute 85 below the hopper for delivering coins to the upper end of said drum, a rotatable feeder in said chute for moving coins in predetermined quantities, there being a restricted laterally extending passage between the 40 hopper and the feeder space, whereby said feeder will lift a predetermined quantity of coins above said passage and discharge them into the lower end of said chute during the latter part of its revolution. 45
- 10 10. In a coin sorter, the combination of an inclinable supporting frame including spaced end plates and strut members rigidly connecting said plates, a screen sorting drum disposed between said end plates and including a shaft journaled in said end plates, 50 coin-introducing means carried by one of said end plates, and coin discharge means carried by the other end plate.
- 20 25 8. In a coin sorter, the combination with a base, of an inclined drum-supporting frame pivotally mounted thereon to swing in a vertical plane, adjustable means for securing said frame in an inclined position, a rotatable sorting drum journaled in said frame, means carried by the frame for introducing coins into the upper end of said drum and for delivering sorted coins from

In testimony whereof I affix my signature.
FRANK E. HAGEMAN.
